UNITED STATES PATENT OFFICE.

CHARLES PICHARD AND EMILE PICHARD, OF PARIS, FRANCE.

PROCESS OF CARROTING HIDES AND SKINS.

No. 873,594.

Specification of Letters Patent.

Patented Dec. 10, 1907.

Application filed July 16, 1907. Serial No. 384,077.

To all whom it may concern:

Be it known that we, CHARLES PICHARD and EMILE PICHARD, citizens of the Republic of France, residing in Paris, in said Republic, 5 have invented certain new and useful Improvements in Processes of Carrotting Hides and Skins, of which the following is a specification.

This invention relates to an improved 10 process of carroting hides, pieces of hides, and skins.

In Letters Patent No. 846,944, dated March 12, 1907, which were granted to us heretofore, compressed air for spraying the 15 carroting liquid onto the hides and the hair of the same was used. Compressed air was used, first, to raise the hair by forcible impact, and, secondly, to carry the liquid carroting material down to the roots of the hair, 20 whether intended for carroting or for dyeing.

By a number of experimental tests it was found that the compressed air can be advantageously replaced by any other suitable fluid under pressure, and more particularly 25 by steam. The jet of liquid is applied at an acute angle to the hides and skins so as to raise the hair and attack the roots by the vapors.

The apparatus which is shown and described in our prior patent referred to is not 30 changed at all, but simply a jet of steam is used instead of compressed air. The temperature and the pressure of the steam are varied in accordance with the kind of work

that has to be done. The advantages of 35 steam, however, consist in the fact that instead of carroting hides at ordinary temperature, they are treated at a higher temperature, and thereby the carroting liquid is introduced at nearly the temperature of the 40 steam, so that the effect of the same on the hides and skins is considerably enhanced.

Having thus described our invention, we claim as new and desire to secure by Letters 45 Patent:

1. The process herein described of carroting hides and skins, which consists in subjecting the hides and skins to the action of a jet of carroting liquid vaporized by steam so that the hairs are raised and their roots exposed by the action of the spray of carroting 50 liquid.

2. The process herein described of carroting hides and skins, which consists in subjecting the hides and skins to the action of a jet of carroting liquid sprayed under pressure of steam while fed in the direction of an acute angle to the hides or skins, so that the hairs are raised and their roots exposed by the action of the spray of carroting liquid. 55

In testimony whereof we have signed this specification in the presence of two subscribing witnesses.

CHARLES PICHARD.
EMILE PICHARD.

Witnesses:

EMILE LEDRET,
H. C. COXE.
